US00D779486S

(12) **United States Design Patent** (10) **Patent No.:** **US D779,486 S**
(45) **Date of Patent:** **** Feb. 21, 2017**

(54) **HEAD MOUNTED DISPLAY**

(71) Applicant: **HTC CORPORATION**, Taoyuan (TW)

(72) Inventors: **Claude Zellweger**, San Francisco, CA (US); **Brent Edward Barberis**, San Francisco, CA (US); **Catherine Sayim Kim**, San Francisco, CA (US); **Carl Samuel Conlee, IV**, San Francisco, CA (US); **Benjamin Kai Norman Robertson**, San Francisco, CA (US)

(73) Assignee: **HTC Corporation**, Taoyuan (TW)

(**) Term: **15 Years**

(21) Appl. No.: **29/568,659**

(22) Filed: **Jun. 20, 2016**
